UNITED STATES PATENT OFFICE.

WILLIAM BASSETT, OF BROOK, INDIANA.

HEATING ATTACHMENT FOR MOTOR VEHICLES.

Application filed March 6, 1924. Serial No. 697,324.

To all whom it may concern:

Be it known that I, WILLIAM BASSETT, a citizen of the United States, residing at Brook, in the county of Newton and State 5 of Indiana, have invented certain new and useful Improvements in Heating Attachments for Motor Vehicles, of which the following is a specification.

This invention relates to new and useful 10 improvements in heating attachments for motor vehicles, and has for its principal object to provide a means whereby the exhaust gases of the internal combustion engine of the motor vehicle may be utilized for heating 15 the radiator during cold weather.

A further object of the invention is to provide a device of the above mentioned character wherein the exhaust gases are further utilized for heating a foot warmer 20 provided in any convenient manner in the floor board of the motor vehicle whereby the occupants of the same may keep their feet warm.

A further object of the invention is to provide a heating attachment of the above mentioned character, wherein means is provided for preventing the exhaust gases from entering the heater when it is not desired to use the latter.

30 A further object of the invention is to provide a device of the above mentioned character, which is simple in construction, inexpensive, strong and durable and further well adapted for the purpose for which it 35 is designated.

Other objects and advantages of this invention will become apparent during the course of the following description.

In the accompanying drawing forming a 40 part of this specification and in which like numerals designate like parts throughout the same:

Figure 1 is a plan view of my invention showing the same in position on a motor 45 vehicle.

Figure 2 is a longitudinal sectional view of the radiator heater.

Figure 3 is an enlarged end elevation of the radiator heater showing the valve 50 thereof.

In the drawing wherein for the purpose of illustration is shown the preferred embodiment of my invention, the numeral 1 designates an elongated pipe, the inner end of 55 which is connected by a suitable coupling such as is shown at 2 to the exhaust pipe A

whereby the inner end of the pipe 1 is adapted to communicate with the exhaust pipe for the purposes hereinafter to be more fully described. Extending transversely from the 60 pipe 1 and connected thereto by means of the coupling 3 is the inwardly disposed portion 4 of the elongated pipe 5. The pipe 5 extends longitudinally on the opposite side of the exhaust pipe A and is supported on the 65 chassis or frame of the vehicle B in any suitable manner. The forward end of the elongated pipe 5 is disposed inwardly as shown at 6 in the drawing and is adapted to fit in one end of the elongated tubular heater 7 70 which is adapted to be supported in any appropriate manner in the bottom of the radiator C. The heater pipe 7 is provided with spaced apertures 8 for the purpose of permitting the exhaust gases passing therethrough and discharged in contact with the 75 radiator for heating the contents thereof. The opposite end of the heater pipe 7 is provided with an enlarged central opening 9 and cooperating therewith is the slidable 80 valve plate 10. The latter is slidably supported on the bolts 11 and 12 respectively, which extend outwardly from the before mentioned end of the pipe 7 and suitable coil 85 springs or the like such as are shown at 13, are disposed around each of the bolts between the heads thereof and the outer face of the valve plate 10 for normally holding the valve over the opening 9. This construction provides a safety valve which protects 90 heater pipe 7 from exploding as a result of a misfire in the exhaust pipe.

Extending around the inwardly extending portion 4 of the elongated pipe 5 is the cylindrical casing 14 and the same is supported 95 on the inwardly extending portion 4 of the pipe 5 in any suitable manner and has an upper portion adapted to extend through the floor board of the motor vehicle in any suitable manner. This casing 14 provides a foot warmer whereby the occupants of the car 100 may keep their feet warm when in engagement with the upper portion of the casing 14 when the device is in operation.

Mounted in any suitable manner within 105 the coupling 3 which connects the inner end of the inwardly extending portion 4 of the pipe 5 with the exhaust pipe 1, is a two-way valve of the well known construction, and it is not thought necessary to go in detail relative to the same as any conventional type of 110 two-way valve may be used for the purposes

of carrying out the objects of the present invention. The valve control arm is shown at 15 and the outer end thereof is connected by means of a link 16 to the rod 17 which is pivoted intermediate its ends as shown at 18 in the drawings, directly beneath the floor board and the forwardly extending end of the rod 17 is connected to a suitable manually controlled lever 19 which extends 10 upwardly through a suitable opening provided in the floor board and within easy access to the operator of the vehicle. For the purpose of normally keeping the valve in the exhaust pipe 1 open and the valve in 15 the inwardly extending portion 4 of the pipe 5 closed, a suitable coil spring, such as is shown at 20 in the drawing, is provided.

The operation of my device may be briefly stated as follows. In the warm weather, 20 when it is not desired to heat the water in the radiator and to use the foot warmer, the valve in the exhaust pipe 1 will be normally in an open position whereby the exhaust gases from the exhaust manifold will be caused to pass therethrough and be emitted from the outer end of the pipe 1 in the usual manner. It is to be understood that when the valve in the pipe 1 is open, the valve in 25 the inwardly extending portion 4 of the pipe 5 is closed thereby preventing any exhaust gases from the pipe 1 from entering the pipe 5.

During the cold weather, the water in the 30 radiator usually has a tendency to freeze and to prevent the freezing of the water whereby the operation of the vehicle is enhanced, the radiator heater 7 is provided, and also provided in conjunction therewith, is the 35 foot warmer 14. When it is desired to place these heaters in operation, the lever 19 is actuated so that the valve arm 15 will be 40 swung in such a manner as to close the outlet in the pipe 1 and open the valve in the inwardly extending portion 4 of the pipe 5 whereby the exhaust gases from the 45 exhaust manifold will pass through the pipe 1 into the inwardly extending portion 4 of the pipe 5 causing heat to be transmitted to the cylindrical casing 14, the exhaust gases 50 passing through the pipe 5 into the elongated tubular heater 7 supported in the bottom of the radiator where through the 55 openings 8, the exhaust gases will be discharged in contact with the radiator thereby heating the same and keeping the same in a warm condition. As stated before, the 60 safety valve 10 will prevent any danger of explosion and the pressure at which the valve is adapted to actuate may be controlled by the adjustment of the bolts 11 and 12. Any suitable means may be provided for keeping the lever 19 in a rearward position whereby the exhaust gases from the exhaust pipe may

be utilized for heating the radiator and foot warmer respectively. If desired, an additional radiator heater could be positioned in front of the radiator and connected to the pipe 5 in any suitable manner. This however is only necessary in places where the weather is extremely cold and the use of one 65 radiator heating pipe would be insufficient to properly carry out the functions of the present invention.

It will thus be seen from the foregoing description, that a heater attachment for 70 motor vehicles has been provided which is very simple in construction, inexpensive, strong and durable, and will not in any way interfere with the operation of the parts of the machine from which the same is applied 75 or necessitate a structural changing of the several parts of the motor vehicle.

While I have shown the preferred embodiment of my invention, it is nevertheless to be understood that various changes in the 80 size, shape and arrangement of parts may be resorted to without departing from the spirit of the invention or the scope of the appended claims.

Having thus described my invention, what 85 I claim is:

1. In combination with a motor vehicle including the exhaust pipe of the internal combustion engine and radiator thereof; of a heater for said radiator connected to said 90 exhaust pipe and comprising an elongated cylindrical perforated casing supported at the bottom of said radiator, the outer free end of said casing having an opening provided therein, a cover plate for said opening, and means for normally keeping said cover plate in engagement with said opening.

2. In combination with a motor vehicle including the exhaust pipe of the internal combustion engine and radiator thereof; of a heater for said radiator connected to said 100 exhaust pipe and comprising an elongated cylindrical perforated casing supported at the bottom of said radiator, the outer free end of said casing being provided with a central opening, a pair of horizontally and outwardly extending bolts carried by the before mentioned outer free end of said casing, a cover plate slidably supported on 105 said bolts adapted to cooperate with the openings formed in said end, and coil springs disposed between the heads of said bolts and said cover plate for normally keeping the latter in engagement with said 110 opening, and means for preventing the exhaust gases from exhaust pipe from entering said heater.

In testimony whereof I affix my signature.

WILLIAM BASSETT.
